UNITED STATES PATENT OFFICE.

ANSEL FREELAND, OF NEVADA, IOWA.

DISPLAY CONTAINER.

Application filed January 30, 1922. Serial No. 532,631.

To all whom it may concern:

Be it known that I, ANSEL FREELAND, a citizen of the United States of America, and resident of Nevada, Story County, Iowa, have invented a new and useful Display Container, of which the following is a specification.

An object of this invention is to provide an improved construction for a display 10 container for the display of vegetables and fruit conveniently for examination by a purchaser and handling by a salesman.

A further object of this invention is to provide an improved construction for a display 15 play container to hold and display vegetables and fruits and having a partition dividing the container into compartments, a large one for storage and a small one for display.

Still a further object is to provide a display 20 play container constructed so that a small portion of the commodity therein can present a relatively large display surface where- by the display compartment will still remain full when most of the commodity has been 25 removed from the storage compartment.

My invention consists in the construction, arrangement and combination of elements hereinafter set forth, pointed out in the claim 30 and illustrated by the accompanying draw- ing, in which—

Figure 1 is a front elevation of a counter containing my improved display container. Figure 2 is an end elevation of the same. Figure 3 is a cross-section on the indicated 35 line 3—3 of Figure 1. Figure 4 is a perspective view of my improved display container.

A counter 10 may be used for supporting a battery of my display containers 25 and may be of any desired dimensions; such as 40 the one illustrated which is of greater height than width and has its length divided into substantially equal units of structure, each of the units being further subdivided into compartments.

In the construction of the counter 10 as 45 shown a series of compartments 23 and 24 are provided for receiving the containers 25. The sills 12 provide supports and slide-ways in the bottoms of the compartments 23, 24, 50 for the containers 25, which are slidably mounted thereon. Other compartments 22 may also be provided for market baskets or other containers 32 which rest on a horizontal partition 14. A counter top 21 may be 55 placed on top of the counter 10 through which the contents of the container 32 may be

viewed. Each container 25 preferably is made of sheet metal with a plane bottom 11, inclined end-walls 26, 27 and side walls 13 perpendicular to the bottom, the upper 60 margins of the end and side walls being rolled. Each side wall of the container is shaped as an irregular pentagon, its upper margin being in two inclined planes having an apex at 28; and a transverse partition 29 connecting the parallel side walls, of the container 25, coincident with said apex. The transverse partition extends slightly more than one-half the width of the side-walls 65 and is spaced from and in a plane perpendicular to the bottom of the container and divides the container into a display compartment 25^a and a storage compartment 25^b. Looped handles 30 and 31 are pivoted on and normally depend from the outer faces of 70 the end-walls 26, and 27 of each container and are adapted for use in withdrawing the container from the counter and for carrying said container. Vegetables of various kinds, such as potatoes, yams, onions, carrots, cabbage, and the like, may be contained in heap- 75 ing measure in the containers 25, and said containers slidably mounted on the sills 12 and within the compartments 23 and 24, the walls 26 abutting the upper inner edges of 80 the base board 16 and extending outwardly over said base board in such manner as to present the contents at one side of the partition 29 for convenient view and inspection 85 by a customer in front of the counter and to present the contents at the other side of said partition, the rear side thereof, for convenient handling by a salesman or clerk. The customer may well be served with articles 90 removed from the container at the rear of the partition 29 and, when that portion of the container is emptied it will be replenished by articles moving by gravity beneath and rearwardly of said partition. The containers may be removed and replaced selec- 95 tively by manual movement on the slideways or sills 12 for exchange or replenishing. The inclined rear end portions of the containers 25 extend rearwardly of the counter 100 for the convenience of salesmen. The slanting front wall 26 of the container 25 and the top of the partition 29 being higher than the top of the wall 26 allows a relatively small quantity of the contents of the container to present a relatively large display 105 surface to the customer. Therefore, the display compartment 25^a will remain full ex-

110

cept when the last small quantity of the contents remains to be sold. The inclined rear wall 27 facilitates scooping the contents of the container 25 from the storage compartment 25^b.

Some changes may be made in the construction, and arrangement of the various parts of my invention, without departing from the real spirit and purpose of my invention, and it is my intention to cover by my claim, any modified forms of structure or use of mechanical equivalents, which may be reasonably included within their scope.

I claim as my invention:

15 A display container including a bottom, side walls and end walls, the end walls of said container being inclined upwardly and outwardly from the bottom, a partition member extended between the side walls and secured thereto, said partition member being spaced above the bottom of the container and

dividing the container into compartments so that commodities from one compartment can pass into the other below said partition, the top of said partition being substantially 25 higher than the tops of said end walls, said side walls being of the same height as said partition at the points where said partition is secured thereto and slanting down in both directions from said points so as to be the 30 same height as the end walls at the points where said end walls are secured thereto, one compartment being comparatively small relative to the other so that it can be used as a display compartment and the large compartment can be used as storage compartment.

Signed at Nevada, in the county of Story and State of Iowa, this 2nd day of January, 1922.

ANSEL FREELAND.
